UNITED STATES PATENT OFFICE.

JOSEPH F. KAYER, OF PHILADELPHIA, PENNSYLVANIA, ASSIGNOR TO
GENERAL ELECTRIC COMPANY, A CORPORATION OF NEW YORK.

SWITCH FOR ELECTRIC LAMPS.

SPECIFICATION forming part of Letters Patent No. 697,727, dated April 15, 1902.

Application filed March 10, 1899. Serial No. 708,615. (No model.)

To all whom it may concern:

Be it known that I, JOSEPH F. KAYER, a citizen of the United States, residing at Philadelphia, in the county of Philadelphia, State 5 of Pennsylvania, have invented certain new and useful Improvements in Switches for Lamp-Sockets, (Case No. 865,) of which the following is a specification.

My present invention relates to sockets for 10 incandescent lamps, and more particularly to switches for these sockets.

It has for its object to provide in such a construction a key-switch which shall have definite positions, which is capable of 15 continuous rotation in either direction, and which when in alinement with the supporting part of the socket will complete the circuit and when turned crosswise will break it, so that by inspection it may be known whether the 20 lamp is turned on or not, even in case the lamp should be defective and not light. To attain these objects, I arrange a key in the axial line of the socket, the device being especially adapted to brackets or chandeliers 25 like those commonly used for gas-fixtures.

Several important advantages incidental to 30 my construction are that by mounting the key on an axis coincident with that of the lamp and lamp-socket and providing a tubular connection at the side for supporting it the movement in turning off and on a lamp is precisely similar to that in operating a gas-fixture such as employed in chandeliers, and is more easily reached and operated with the 35 arm extended. The socket in which the stem of the lamp is supported is in a vertical line above the operating-key, and the switch mechanism is supported in a casing below the socket and out of range of connection therewith, so that damage by short circuits is impossible.

The invention will be better understood from the accompanying drawings.

Figure 1 is a section showing the construction of the switch and socket. Fig. 2 is a detail in section, taken at a right angle to the section shown in Fig. 1. Fig. 3 is a detail of a modification adapting the device to the well-known Thomson-Houston socket. Fig. 4 is a sectional plan on the line 4 4 of Fig. 1.

Fig. 5 is a detail in plan, and Fig. 6 a detail in perspective, of parts of the switch.

A is a pipe or conduit-tube, to which the device as a whole is secured by the collar A'. Through this pass the circuit-wires a b. 55

B is a spherical shell containing the parts of the switch open at the bottom, the opening being closed by another shell B'. It will be observed that the shell B', which is held in place by suitable screws b', extends slightly 60 above the center of the shell B, and as there is an opening in one side of it at b² it may be sprung over the shell B, and with the screws b' be held securely in place. Thus the switch mechanism is inclosed in a chamber or casing 65 separate from the lamp-socket, and access to its parts is convenient for repairs.

At the top of the structure is the socket, provided with the terminals N' O, and an outer shell M', held in place by the shell M, screw-threaded into the shell B. A ring P, of insulating material, separates the shell M' and the screw-threaded shell O for well-known reasons. These are the parts of the well-known Edison socket. A plate R, of por- 70

celain by preference, supports the terminals of the socket and insulates them from one another. One of the circuit-wires a b is connected to a strip N, the inner circuit-terminal N' (see Fig. 2) being secured to it in any 80 proper way. It is manifest that if an ordinary Edison lamp be inserted in this socket the terminal N' will touch the button on the base of the lamp and the shell O will complete the circuit through it. Screws o o secure the shell O in place and connect it to the spindle E of the switch, which is illustrated in the middle of the figure. A yoke H is mounted upon the spindle, but insulated from it by a bushing or sleeve G. The yoke car- 85

ries a contact h, with which, at h', one of the circuit-wires is connected, the contact h being insulated from the yoke. The ends of the latter project through the shell B' at h², so that it is held stationary. 90

The circuit is made and broken by the plate F, a detail of which is shown in Fig. 6. This is composed of insulating material molded about the contact F', the latter formed with a hub embracing the spindle E. A pin f se- 95

cures the hub to the spindle, and a bushing C, of insulating material, prevents the pin from touching the shell B'. A spring I' holds the yoke H firmly in place.

5 Upon the spindle E (see Fig. 4) is secured a square block K of insulating material with a pin k passing through it, the ends of the pin being sunk within the block. With the block a spring L coöperates to determine positively the position of the spindle. The arrangement is such that when one side of the square is presented to the spring the contact F' (see Fig. 6) registers with the contact h, (see Fig. 1,) thus completing the circuit from contact h through F' and the spindle to terminal O of the socket and back through the terminal N'. In the other position of the key the contact h rests upon the insulation, thus opening the circuit. A shield I, (preferably 20 of insulating material,) having a hole i, through which one of the circuit-wires may pass, prevents the other wire from becoming tangled in the parts of the switch. The shield I might be omitted, if desired.

15 25 To permit the snap action of the switch, the spindle E has a bushing E², of insulating material, interposed between it and the handle E'. A pin e driven into the spindle is insulated from the handle by a bushing e'. This 30 allows of lost motion between the handle and the spindle sufficient to permit the switch to snap in a well-known manner when the block K turns from one position to the other.

35 Fig. 3 shows the adaptation of the socket to the well-known Thomson-Houston system. In this the center or screw terminal is lettered N² and the ring-terminal O'. In order to effectively insulate the center terminal from the spindle, a cup Q, of insulating material, is placed over the latter within the usual yoke which is employed to connect the spindle through the screws o o to the ring-terminal O'.

40 45 What I claim as new, and desire to secure by Letters Patent of the United States, is—

1. A socket for an incandescent lamp, provided with a holder for the lamp-base, a casing for the switch mechanism, a key having its operating-stem in a line axial to the holder,

a fixed contact yieldingly mounted in a vertical plane, a movable contact rotated by the key-stem in coöperative relation to the fixed contact, and means for effecting a snapping rupture of the circuit when the contacts separate.

50 55 2. A socket for incandescent electric lamps, provided with a receptacle for the lamp-base, a casing connected to the bottom thereof and separable therefrom, switch mechanism housed within the casing, a lateral pipe connection in the casing through which the current-leads may be led, and a key below the casing turning on a plane transverse to the axis of the lamp and socket.

60 65 3. A socket for incandescent electric lamps, provided with a receptacle for the lamp-base, a casing below the same, snap-switch mechanism within the casing, said casing being formed of separable parts to admit access to its interior, a lateral pipe connection from the 70 casing for connection with a tubular bracket to house the current-leads, and a key controlling the switch turning on a plane transverse to the axis of the lamp-socket.

75 80 85 4. A socket for incandescent electric lamps, provided with a receptacle for the lamp-base mounted on an insulating-support, means thereon for effecting connection with the lamp-terminals, a casing mechanically connected with the socket, provided with a lateral tubular connection for the circuit-leads, a switch in said casing composed of an elastically-mounted terminal, a rotatable contact coöperating therewith, a key on the bottom of the casing mounted to turn in a plane transverse to the axis of the lamp and socket, a lost-motion connection being provided between the key and the movable contact, and a spring and cam controlling the movement of the contact to effect a snapping motion on 90 opening the circuit.

85 In witness whereof I have hereunto set my hand this 4th day of March, 1899.

JOSEPH F. KRAYER.
